UNITED STATES PATENT OFFICE.

STANISLAW PAUL ZYWNO, OF MIDDLETOWN, CONNECTICUT.

FLYING-MACHINE.

1,241,072.

Specification of Letters Patent. Patented Sept. 25, 1917.

Application filed January 16, 1917. Serial No. 142,626.

To all whom it may concern:

Be it known that I, STANISLAW PAUL ZYWNO, a citizen of Russian Poland, residing at Middletown, in the county of Middlesex and State of Connecticut, have invented 5 certain new and useful Improvements in Flying-Machines, of which the following is a specification.

My invention relates to improvements in 10 flying machines, and the object of my improvement is to produce a flying machine that operates by the vibration of a pair of wings after the manner of a bird.

In the accompanying drawing:

15 Fig. 1 is a plan view of my improved flying machine.

Fig. 2 is a sectional view on the line $\alpha\alpha$ of Fig. 1.

20 Fig. 3 is a rear elevation on an enlarged scale of the main shaft and crank arms.

Fig. 4 is a similar view of the main gear and connected gearing.

Fig. 5 is a side elevation of the same.

25 Fig. 6 is a rear elevation of the controller arm and connected parts.

Fig. 7 is a side elevation of the same.

Fig. 8 is a side elevation of the machine, on the same scale as Fig. 1.

30 My improved flying machine comprises a pair of lateral wings 10 positioned one on each side of a central house or cab structure 11 that are supported and inter-connected so as to vibrate in unison, and operated by a motor 12 of any suitable form.

35 The house 11 is a skeleton structure of appreciable width and length and is covered with a roof 13 of thin sheet aluminum or other sheet material, the said roof 13 being of suitable area to have an appreciable 40 effect as an air plane when the machine is operated at high speed. The side walls 14 support near the upper end a transversely extending control shaft 15, the ends 16 of which project outwardly laterally, and below the control shaft 15 is a countershaft 17. On the control shaft 15 is mounted a control gear 18 that co-operates with a sector 19.

45 The said sector 19 is provided on the upper end of an arm 20 that is mounted on 50 the countershaft 17, the said arm 20 extending downwardly within the house 11 and being provided with means for being moved to different positions and for being locked in any particular position to which it may

be set. By moving the arm 20 back and forth the control shaft 15 is rotated correspondingly, and the wings 10 are so connected to the control shaft 15 that they are tilted as the control shaft 15 is rotated.

55 As one means of operating the arm 20 I provide on the lower end thereof a second sector 50 that engages with a worm 51 provided on the worm shaft 52.

60 At one end of the worm shaft 52 and located in a convenient position to be manipulated by the operator I provide a crank arm 53.

65 The wings 10 are connected to the ends 16 of the control shaft 15 by a pivotal connection 21 that permits of a generally up and down swinging movement of the wings 10.

70 The lower part 22 of the house 11 is formed suitably to provide a bed for the motor 12 and to support the middle part of the main shaft 23. Extending downwardly 75 from the house 11 is a cradle structure 24 that is provided with a pair of wheels 25 of the usual form.

75 At the lower part of the house 11 and extending laterally from the bed 22 and along the main shaft 23 is a frame 26 of suitable light and strong construction for operatively supporting the outer end portions of the main shaft 23.

80 The main shaft 23 is provided at about the middle with a main gear 27 that is operatively connected with the motor 12 by a set of gears 28 and at the ends is provided with a pair of crank arms 29 that are connected with the wings 10 in a manner to be described. The connections to the crank arms 29 comprise in each case a block 30 pivotally mounted on the crank pin 31, the said block 30 having on the upper end a 85 short, longitudinally extending pivotal pin 32 that serves as the means for connection with the upwardly extending connecting rod 33, the said connections consisting in each case as described of a combination that permits of raising and lowering the connecting rod 33 and at the same time permits of swinging the same back and forth, after the manner of a universal joint.

90 The upper end of the connecting rod 33 100 is provided also with a universal joint 34 that serves as the means for connection with the lower end of a strut or rod 35 that serves

as a part of the bracing structure for the frame-work of the wings 10.

The wings 10 extend laterally from the ends 16 of the control shaft 15 and are built up of a border frame 36 having a longitudinal cross-rib 37 at about the middle and covered with a web 38 of thin sheet aluminum, being of about the same length as the house 11 and having a lateral extent of 10 about three times the width of the said house 11. The border frame 36 may be of shallow V-shape along the edge opposed to the house 11, the front edge 40 and rear edge 41 being directed laterally in parallelism, 15 and the outer lateral edge 42 being rounded as shown. At the middle of the longitudinal cross-rib 37 is the downwardly directed strut rod 35 on the lower side and on the upper side is the upwardly directed strut rod 42, the lower strut rod 35 being connected to 20 the connecting rod 33 as described, and from the ends of the said strut rods 35 and 42 is provided a net-work of strain or tie wires, comprising the upper set 43 of tie wires 25 on the upper side and the lower set 44 of tie wires on the lower side, the outer ends of the wires being connected to different parts of the border frame 36 suitably to reinforce the same.

30 Extending rearwardly from the house 11 is structure and mechanism of ordinary form, comprising the tail structure 45, the lateral rudder 46 at the rear end thereof, and adjacent the said rear end is a pair 35 of laterally positioned elevation control wings 47.

Lines 48 are connected to the end rudder 46 to move the same from side to side to control the lateral direction of movement 40 and lines 49 connected to the shaft 54 of the elevation control wings 47 operate to control the angular position of the same to control the upward and downward movement, the control wings 47 being tilted in 45 the usual manner to effect a change in the upward or downward direction.

The elevation control wings 47 are used 50 ordinarily to control upward and downward movement for a particular setting of the main wings 10, and the latter are tilted by operating the arm 20 to effect a more pro-

nounced and sudden change in the upward or downward direction.

The main wings 10 for a particular setting of the handle 20 have their inner ends 55 essentially fixed and as the crank arms 29 are rotated they are vibrated to and fro through a definite angle, and they are so positioned that such angular movement extends across the line of the control shaft 15 to which they are connected. When the main wings 10 are tilted so that they are inclined from the rear downwardly relatively to the direction of movement and they are vibrated at a high rate of speed the 60 operation on the air is such as to elevate the machine, the rate of vibration being so rapid that the air offers resistance that is positive and momentarily essentially like a solid or liquid body.

As described the motive feature of my flying machine comprises a pair of vibrating wings, operated by a suitable motor, and in conjunction therewith the house with its flat covered roof operates as a diminutive 65 plane for steadyng the movement.

I claim as my invention:

In combination in a flying machine, a house having a skeleton frame structure, a tail structure extending rearwardly from 80 the said house, a lateral rudder mounted on the end of the said tail, a pair of elevation control wings mounted on the said tail, means for tilting the said wings, an air plane serving as the roof for the said house, 85 a control shaft extending through the upper part of the said house, means for rotating the said control shaft, a main shaft extending through the said house, a motor operatively connected to the said main shaft, 90 crank arms on the ends of the said main shaft, a pair of main wings connected each by one end to one of the ends of the said control shaft, and connecting rods serving to operatively connect the body portion of 95 each of the said main wings with one of the said crank arms.

STANISLAW PAUL ZYWNO.
